UNITED STATES PATENT OFFICE.

JAY WILCOX, OF GRAND RAPIDS, MICHIGAN.

VALVE FOR SPRAYING-MACHINES.

1,135,342.

Specification of Letters Patent. Patented Apr. 13, 1915.

Application filed March 27, 1914. Serial No. 827,752.

To all whom it may concern:

Be it known that I, JAY WILCOX, a citizen of the United States, residing at Grand Rapids, in the county of Kent and State of Michigan, have invented certain new and useful Improvements in Valves for Spraying-Machines, of which the following is a specification.

My invention relates to improvements in valves for use on spraying machines, and its objects are, first, to provide a valve with which an even pressure may be insured at the nozzle, and, second, to provide a means whereby the valve will drain itself at a given pressure, and will drain all sediment from the receiving chamber so there will be no danger of cementing the valve in its seat by the accumulation of sediment around the valve. I attain these objects by the mechanism and construction shown in the accompanying drawing, in which—

Figure 1 is a vertical section of the valve practically on the line *a a* of Fig. 2. Fig. 2 is an elevation of the barrels of the valve assembled and in condition for use and Fig. 3 is a section of the valves showing the manner of connecting them with the connecting rod.

Similar numerals refer to similar parts throughout the several views.

In the construction of this valve I make use of two barrels or chambers 1 and 2. These barrels may be connected by any available form of coupling, but I prefer that the form shown in the drawing be used, as the action is more direct, the expense reduced to the minimum, and the efficiency is raised to the maximum. 1 represents the receiving barrel and the spraying material is supposed to be forced into this chamber through the pipe or opening 6 when it is forced upward through the neck or coupling 3, past the valve 4 into the barrel or chamber 2, and thence through the opening or pipe 7 to the spraying tube, not here shown, as it forms no direct part of the invention herein desired to have covered. The pipe 12, that extends downward from the barrel 1 is open its entire length but is provided with a valve 5 that is held firmly in place by the pressure of the spraying material in the barrel 1, and the valve 4 is as firmly seated by pressure in the barrel 2, caused by forcing it into said barrels faster than it can be forced out of the spraying tube.

The barrel 2 is made open at the upper

end and a diaphragm 14 is placed in position, as indicated, and held in place against the pressure in the barrel by any available means, as, for instance, a ring, 13, anchored in the top of the barrel and held in place by the girder 8, or other suitable means.

The diaphragm 14 performs a double service, first, to regulate the pressure in the barrel 2, and, second, to actuate the rods 9 that raise the valve 5 to reduce the pressure in said barrel and allow sediment to flow out. As it is necessary to adjust the diaphragm to sustain different pressures in the chamber, I pass a bolt 11 through the girder 8 and place a spring 10 between the end of this bolt and the surface of the diaphragm, around the standard 15, so that greater or less pressure may be exercised upon the upper surface of the diaphragm as may be necessary to maintain the desired pressure at the nozzle, or in the chamber 2. The bolt 11 is hollow so the standard 15 may pass through freely, and the rods 9 are supported on its upper end so that any movement of the standard, vertically, by the movement of the diaphragm, is communicated to the rods 9. These rods are bent upward at the lower ends, and pass upward in the drain pipe 12 in position to be made to raise the valve 5 as the diaphragm is forced upward by the pressure within the chamber 2, thus, when the pressure in the chamber 2 has been raised above the capacity of the spraying pipe the diaphragm 14 will be forced upward and the valve 5 will be raised so that any sediment in the lower chamber, 1, may flow out through the pipe 12 into the supply tank, or other desired receptacle, and at the same time the pressure in the barrels will reduce until the diaphragm will assume its normal position reseating the valve 5 and causing the inflow of material into the chamber 1 to again hold and increase the pressure in the barrels, as desired or necessary.

When the pumps are idle and all pressure removed from the chambers the rods 9 may be raised upward and the valve 5 released or raised from its seat so that all the contents of the chamber 1 may flow out, and, if desired, the valves may be drilled to a given depth and a rod 16 applied in such a manner that by raising the lower valve, 5, a little higher than the diaphragm would naturally raise it the upper valve, 4, will be raised from its seat so the

chamber 2 may be drained. This is done by raising the rods 9 independent of the diaphragm, which may be done by hand after the pressure has escaped from the 5 chamber 1.

One of the main advantages gained by my construction is that I do away with all necessity for packing any single feature in the device, this being brought about by 10 placing the actuating rods 9 outside of the barrels and then bending the lower ends upward and passing them through the pipe 12 in such a manner that they will raise the valve 5 when the diaphragm is made to 15 move upward. It will be readily understood that with packing around actuating rods, valves, &c., the sediment that settles from the spraying material will soon become hard and adhere to the several parts that are 20 packed, and render the machine inoperative while with my machine this is impossible as I am enabled to drain all sediment out of the machine and hold all parts free for immediate use without the necessity of opening and cleaning. 25

The lower end of the rod 16 is securely connected with the valve 5, and the upper end of said rod is loosely fitted in the opening α in the upper valve, 4, with some distance between the end of the rod and the top of the opening when both valves are seated, so the valve 5 may be raised off of its seat by the diaphragm 14 without affecting the valve 4, and so that by raising the 30 valve 5 a little higher the valve 4 will be raised off of its seat, as hereinbefore suggested.

What I claim as new, and desire to secure by Letters Patent of the United States, 40 is:

1. In a valve for spraying machines, a receiving barrel and a discharge barrel, a check valve in each barrel, and a diaphragm in the discharge barrel, with a regulating 45 device connected with the diaphragm, rods

arranged to be actuated by the diaphragm, and extending downward outside of the valve barrels with the ends extending upward to be made to raise the check valve in the receiving barrel as the center of the 50 diaphragm is forced upward.

2. In combination with a receiving barrel, the discharge barrel, the diaphragm and check valves of a valve for spraying machines, a girder above the diaphragm, a hollow bolt passing through said girder, a standard passing through said bolt and resting on the diaphragm, a spring around said standard between the lower end of the hollow bolt and the surface of the diaphragm, 60 a pipe extending downward from the receiving barrel, rods supported on the standard and extending downward outside of the barrels and then bent upward to pass up into the pipe and actuate the valve from 65 the movements of the diaphragm.

3. In combination with the receiving barrel, the discharge barrel, a check valve in each barrel, the diaphragm, and a regulating device for the diaphragm with a pipe 70 extending downward from the receiving barrel, rods supported to be actuated by the movements of the diaphragm and extending downward outside of the barrels with the lower ends bent and extending upward 75 to position to actuate the valve in the receiving barrel with the movements of the diaphragm and a rod extending loosely into the ball in the receiving barrel and extending upward and into a hole in the valve in 80 the discharge barrel so that both valves may be raised simultaneously with the actuating rods.

Signed at Grand Rapids Michigan March 21, 1914.

JAY WILCOX.
